UNITED STATES PATENT OFFICE

98,798

DESIGN FOR A COMBINED LAMP AND ASHTRAY

Harold De Garro, Los Angeles, Calif.

Application November 11, 1935, Serial No. 59,473

Term of patent 3½ years

To all whom it may concern:

Be it known that I, Harold De Garro, a citizen of the United States, residing at Los Angeles, in the county of Los Angeles and State of California, have invented a new, original, and ornamental Design for a Combined Lamp and Ash Tray, of which the following is a specification, reference being had to the accompanying drawing, forming part thereof.

I claim:

The ornamental design for a combined lamp and ashtray as shown.

Signed at Los Angeles, in the county of Los Angeles, State of California, this 31 day of October, 1935.

HAROLD DE GARRO.
